[57] CLAIM

The ornamental design for a package for cigarettes, as shown and described.

DESCRIPTION

FIG. 1 is a front, right, top perspective view of a package for cigarettes in the closed position, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front, right, top perspective view of a package for cigarettes in the open position, showing my new design;

FIG. 9 is a front elevational view showing the interior portion of the package for cigarettes as illustrated in FIG. 8;

FIG. 10 is a rear elevational view of the package for cigarettes as illustrated in FIG. 8;

FIG. 11 is a right side elevational view of the package for cigarettes as illustrated in FIG. 8;

FIG. 12 is a left side elevational view of the package for cigarettes as illustrated in FIG. 8;

FIG. 13 is a top plan view showing the interior portion of the package for cigarettes as illustrated in FIG. 8; and,

FIG. 14 is a bottom plan view of the package for cigarettes as illustrated in FIG. 8;

*Fig.1.**Fig.2.**Fig.3.**Fig.4.**Fig.5.**Fig.6.**Fig.7.**Fig. 9.*

*Fig. 10.**Fig. 11.**Fig. 12.**Fig. 13.**Fig. 14.*
